UNITED STATES PATENT OFFICE.

HERBERT H. STEELE, OF MARCELLUS, NEW YORK, ASSIGNOR TO THE MONARCH TYPE WRITER COMPANY, OF SYRACUSE, NEW YORK, A CORPORATION OF NEW YORK.

TYPE-WRITING MACHINE.

1,010,087.

Specification of Letters Patent. Patented Nov. 28, 1911.

Application filed July 9, 1910. Serial No. 571,150.

To all whom it may concern:

Be it known that I, HERBERT H. STEELE, a citizen of the United States, and resident of Marcellus, in the county of Onondaga and State of New York, have invented certain new and useful Improvements in Type-Writing Machines, of which the following is a specification.

My invention relates to ribbon mechanism for typewriting machines and its object, generally stated, is to provide improved mechanism of the class specified.

More specifically my invention has to do with the provision of improved mimeograph devices whereby the use of the ribbon may be dispensed with at pleasure when it is desired to write a stencil or mimeograph sheet or for similar purposes.

Another object of the invention is to provide means for varying the normal position of the printing portion of a vibratory ribbon in combination with means for vibrating said printing portion different extents from a plurality of normal positions.

To the above and other ends my invention consists in the features of construction, combinations of devices and arrangements of parts hereinafter described and particularly pointed out in the claims.

While my invention may be adapted to various styles of writing machines I have shown it as applied to a Monarch typewriter. In the present instance I substitute for the usual stationary guide for the ribbon carrier, which guide is rigid on the frame, a two-piece guide, one piece pivoted on the other, said two-piece guide being associated with a novel form of ribbon carrier. By manipulating the guide the carrier may be disconnected at one point from the operating lever and another portion of said carrier may be connected with the operating lever, thereby altering the normal position of the ribbon carrier and the printing portion of the ribbon which is within the control of said carrier. Further, means are provided for varying at will the normal relationship between the operating lever and the actuating devices therefor, whereby the extent of movement of the operating lever and the consequent extent of movement of the ribbon carrier may be varied. As a result the ribbon carrier may be moved variable extents from one normal position so as to present different fields of the ribbon

to the printing point and may be moved different extents from another normal position so as either to present one ribbon field to the printing point, or else not to present the ribbon to the printing point at all, thus enabling the types to coact directly with the work sheet or stencil sheet.

My invention will be more particularly explained in connection with the accompanying drawings, wherein—

Figure 1 is a vertical front to rear sectional view of a typewriting machine embodying my invention, so much only of the machine being shown as is necessary to a clear understanding of said invention. Fig. 2 is a diagrammatic view showing parts of the printing portion of a ribbon in the different positions to which the same may be moved in the operation of my invention. Fig. 3 is a perspective view of my improved ribbon carrier or vibrator. Fig. 4 is a perspective view of the guide for said improved ribbon carrier and also of part of the support for said guide. Fig. 5 is a side view partly in section showing the ribbon carrier and its guide and part of the actuating and supporting devices. Fig. 6 is a plan view partly in section of the mechanism for varying the actuating devices for the operating lever. Fig. 7 is a fragmentary side view of a modified construction of ribbon carrier and operating lever.

As appears from Fig. 1 the main frame of the machine comprises a base portion 1 from which rise posts 2 supporting a top plate 3. Key levers 4 are fulcrumed on a plate 5 in rear of the base, each key lever being provided with a restoring spring 6 and being connected with a type bar (not shown) having the usual or suitable construction and mounting. The type bars when actuated are adapted to be swung upward and rearward into coöperation with the front of a roller platen 7, diagrammatically illustrated herein. The platen is mounted on a carriage (not shown) which is connected by a band 8 with a spring drum 9. Letter space movements of the carriage are controlled by escapement devices comprising a toothed escapement wheel 10 and feed dogs 11 and 12, which dogs are supported at the top of a pivoted rocker 13, the horizontal arm whereof is connected by a vertical link 14 with a central arm 15 of a pivoted universal bar frame, said frame

carrying a universal bar 16 which underlies the key levers 4.

A ribbon 17 is wound on horizontal spools 18, one at each side of the machine above the top plate and forward of the platen. Each spool is supported on a vertical shaft 19 which carries at its lower end a beveled pinion 20 meshing with a beveled pinion 21 carried at the forward end of a horizontal shaft 22 bearing in stationary lugs 23 and carrying at its rear end a beveled pinion 24. The two pinions 24 are adapted to mesh alternately with associate driving pinions 25 which are secured on a power or driving shaft 26 which receives rotary motion from the spring drum when the latter turns to draw the carriage in printing direction, the connections between the spring drum and power shaft comprising intermeshing pinions 27 and 28. The spool turning or ribbon feeding mechanism above described is like that of the Monarch typewriting machine, but any other suitable ribbon feeding mechanism may be employed if desired.

Midway between the ribbon spools the ribbon is threaded through a vibratory ribbon carrier or vibrator designated as a whole as 29 and best shown in Fig. 3. The head or upper portion of the ribbon carrier is or may be of ordinary construction comprising hooks 30 off-set laterally from the side arms 31 the inner edges whereof are bent to provide grooves 32. The ribbon passes from the hooks 30 behind the upper portions of the arms 31 and across the open space 33 between said arms. This space or opening 33 is usually called the type opening, the types passing through it to coöperate with the ribbon and the platen. That portion of the ribbon which bridges the type opening is commonly termed the printing portion of the ribbon. The depending part or stem of the ribbon carrier 29 is provided with a central vertical slot 34 which forms two strips or fingers 35. These strips are doubled back on themselves and the two plies or folds are secured together by rivets 36. The rear plies are bent or shaped to provide openings which frictionally hold cross pins 37 and 38 bridging the slot 34 and arranged one above the other and about $\frac{1}{8}$ " apart.

The ribbon carrier is supported and guided on a carrier guide which is best shown in Fig. 4. Said guide comprises two parts 39 and 40. The part 39 is provided with two parallel upwardly extending fingers 41, the inner edges whereof are embraced by the grooves 32 in the ribbon carrier, the construction enabling the carrier to be slid up and down on the guide. The lower side portions of the guide part 39 are bent rearwardly, forming ears 42 which embrace corresponding ears 43 projecting forwardly from the sides of the other guide part 40. This guide part is provided at its

top with a pair of hooks 44 which fit over the top edge of the frame plate 45. A headed screw 46 (Figs. 1 and 5) secures the lower end of the guide part 40 to the frame plate 45. Arranged between the head of this screw 46 and the guide part 40 is the usual cam member 47 which coöperates with the usual card guide 48 shown in Fig. 1 only. The guide parts 39 and 40 are pivotally connected together by a pin or rod 49 which passes through the ears 42 and 43. The rod 49 also provides a bearing for the swinging card guide 48 which as shown in Fig. 1 extends upward between the two guide parts and in rear of the ribbon carrier. A spring 50 (Fig. 4) is coiled around the rod 49 and its ends co-act with the guide parts 39 and 40 to maintain them in the normal relationship shown in Figs. 1 and 4 in which position stop faces 51 formed at the front of the ears 43 contact with the rear face of the part 39. By pressing rearward against the upper portions of the fingers 41 the spring 50 may be overcome and the guide part 39 swung about the pivotal center 49. Since the guide part 39 controls the ribbon carrier 29, the swinging movement of the guide part will be communicated to the ribbon carrier. The swinging movement of the ribbon carrier and guide part may also be caused by pressure applied to the upper part of the ribbon carrier, as well as to the guide part 39. This pivotal movement of the ribbon carrier is to enable one or another of the cross pins 37 and 38 to be disconnected from the operating lever and the other cross pin to be connected therewith. The operating lever 52 is enlarged at its forward end and formed with a horizontal open-mouthed slot 53 in which the cross pins are adapted to engage. The operating lever is fulcrumed at 54 to a lug 55 depending from the top plate 3. As shown in Fig. 1 the rear arm of the operating lever 52 is formed with an arcuate slot 56 which is engaged by a lateral pin 57 secured to the top of a vertically-disposed link 58, the lower end of said link being pivotally connected with the arm 15 of the universal bar frame. It will be understood that when a key lever 4 is actuated the universal bar frame will be swung downward, lowering the link 58 and causing it to swing the operating lever 52 on its fulcrum so as to raise the ribbon carrier and the printing portion of the ribbon. It will be further understood that the extent of movement of the ribbon carrier may be varied by changing the position of the actuating pin 57 in the slot 56, this being accomplished by swinging the link 58 about its pivotal connection with the arm 15. A draw spring 59 connects the links 14 and 58 and tends constantly to swing the link 58 rearward about its pivot. The movements of the link 58 are controlled by a member 60 which is slidably mounted on the

power shaft 26 and is connected to receive rotary movement from said shaft. As shown in Fig. 6 the member 60 comprises three working faces 61, 62 and 63 which are connected by cam surfaces. The faces 61 and 62 are different in diameter but are both concentric with the shaft 26, while the face 63 is eccentric thereto. A hub 64 extends rightward from the member 60 and is formed with a circumferential groove 65. Loosely engaging said groove is a forked arm 66 which is vertically disposed and is provided at its upper end with a hub 67 which fits over and is fixed to the inner end of a slide rod 68. Said slide rod is supported on stationary lugs 69 and carries at its right-hand end a vertical pin 70 which is engaged by the slotted arm of a bell crank lever 71 having a fixed fulcrum 72. A link 73 extending forward beneath the top plate connects the other arm of the bell crank 71 with an arm of a second bell crank 74 which is pivoted at 75 to the under side of the top plate near the front of the machine and has an arm 76 extending forward through a slot in the right-hand front plate 77. The forward end of the arm 76 is provided with a finger piece 78 by which the bell crank 74 may be swung on its pivot, thereby operating through the described connections to slide the rod 68 back and forth in its bearings and vary the position of the member 60 lengthwise of the power shaft 26, thus bringing one or another of the working faces 61, 62 and 63 into coöperation with the link 58.

As is well understood the eccentric face 63 is employed when a uniform ribbon is in use, so as to automatically and progressively 40 vary the throw of the ribbon carrier and obtain a crosswise feeding of the ribbon at the same time that it is fed lengthwise. In the drawing, a two-color ribbon 17 is illustrated, said ribbon 17 being divided lengthwise 45 into fields *m* and *n* which may, for example, be respectively black and red. With such a ribbon it is usual to set the actuating devices by employing the faces 61 and 62. When the working face 61 is in operation 50 as shown in Figs. 1 and 6 the link 58 will be maintained normally in the forward position, the pin 57 engaging with the front end of the slot 56 near the fulcrum of the operating lever. If at this time the lower 55 cross pin 37 is engaged with the operating lever 52, then the printing portion of the ribbon will be normally maintained in the position shown in Fig. 1, and at printing operation will be lifted so as to present the 60 lower field *n* opposite the printing point *p* on the platen. Referring to Fig. 2 wherein the ribbon is represented by small parts or sections and the printing line is represented by the dotted line *p*, *p*, the normal 65 position of the ribbon corresponding with

Fig. 1 is designated as *a* while the abnormal position in which the lower ribbon field is presented opposite the printing line is designated as *c*. If the positioning member 60 be shifted by manipulating the finger piece 78, so as to bring the working face 62 into use, then the link 58 will be drawn back to the dotted line position in Fig. 1 and at printing operation the ribbon carrier will be lifted to the *b* position of Fig. 2, thus presenting the upper ribbon field *m* to the types. It will be observed that as thus far described the operation does not differ materially from that of other two-color ribbon mechanisms heretofore known.

Suppose it be desired to dispense with the use of the ribbon entirely in order that a stencil sheet may be printed or for some other reason, then the upper portion of the ribbon carrier is pressed rearward to the dotted line position of Fig. 5. This results in swinging the lower cross pin 37 out of engagement with the slot 53 in the operating lever. Still holding the ribbon carrier and its guide pressed in against the force of the spring 50, the carrier may be slid down on its guide until the upper cross pin 38 is opposite the slot 53 whereupon the carrier may be released and the spring will force the cross pin 38 into engagement with the operating lever. It will be seen that this change in connection between the ribbon carrier and operating lever is effected without moving or otherwise affecting the operating lever itself. By said change the normal position of the printing portion of the ribbon is changed also, being lowered from the *a* position of Fig. 2 to the position indicated by the letter *x* in said figure. If now the link 58 be set normally in the dotted line position of Fig. 1, it will operate when the printing keys are actuated to raise the printing portion of the ribbon only to the position indicated by the letter *y* in Fig. 2 which is not far enough to bring any portion of the ribbon opposite the printing line on the platen. Consequently the types will move over the top edge of the ribbon without touching the same and will coöperate directly with the work sheet.

Sometimes it is desirable to print a memorandum on the stencil sheet prior to or after completion of the stenciling. In such case the link 58 is shifted forward to the full line position of Fig. 1 and then at 120 printing operation the ribbon will be lifted to the z position in Fig. 2, thus presenting the black field of the ribbon to the types and enabling the explanatory writing or other memoranda to be printed in black on the 125 stencil sheet. It will be observed that the variation in the throw of the vibrator is effected by setting the link 58 and without disturbing the normal position of the operating lever 52. 130

Various changes may be resorted to within the scope of my present invention. An example of such changes is shown in Fig. 7 wherein the ribbon carrier 79 is provided with a single cross pin at its lower end, while the operating lever 81 is provided at its forward end with a downward extension 82, said extension being formed with a slot 83 which is an addition to the usual slot 84 in said lever. The ribbon carrier may be pivotally mounted as in the prior construction and a single cross pin 80 on said carrier may be caused to engage at will with either the slot 84 or the slot 83 so as to obtain substantially the same results as were obtained by the use of the single slot and the two cross pins in the prior construction.

It will be noted that by my present invention I provide a member (in the present instance a lever) which member is combined with means for varying the normal position of the printing portion of the ribbon, said means in the present instance comprising a ribbon carrier or vibrator; that said member is also combined with means which operate to variably move the printing portion of the ribbon at printing operation, this variable moving means comprising a link which is settable in a plurality of normal relationships with said member; that said member has a single normal position; that the ribbon carrier is connectible with said member at any one of a plurality of connecting points; that in the preferred form the ribbon carrier has a plurality of cross pins which are connectible with a slotted operating lever; that the ribbon carrier and the operating lever are combined with means for affording a change in the normal relationship between said carrier and said lever; that the operating lever is connected with a key-operated universal bar by connections which comprise a link; that means are provided for varying the normal relationship of said connections or connecting devices, which means comprise a hand-operated controlling member having a plurality of faces; that said faces are adapted to co-act with a link; that the ribbon carrier is associated with a guide; that said carrier may be vibrated independently of said guide; that the guide may be moved to permit the normal position of said carrier to be varied; that in the present instance this movement of said guide is a pivotal one; that when said guide is turned on its pivot independently of the printing operation of the machine, said carrier is turnable with said guide; and that said guide is spring controlled, the spring operating to restore it to normal position after it has been given a pivotal movement.

What I claim as new and desire to secure by Letters Patent, is:—

65 1. In ribbon vibrating mechanism for

typewriting machines, the combination of a member, means co-operative therewith to afford variations in the normal position of the printing portion of the ribbon, and actuating means co-operative with said member in all of the varied normal positions of the printing portion of the ribbon and adapted to move the printing portion of the ribbon at printing operations variably from a normal position from which the printing portion of the ribbon may start to vibrate. 70 75

2. In ribbon vibrating mechanism for typewriting machines, the combination of a member having a single normal position, means co-operative therewith to afford variation in the normal position of the printing portion of the ribbon, actuating means co-operative with said member to vibrate the ribbon at printing operation, and means for varying the relationship between said member and said actuating means. 80 85

3. In ribbon vibrating mechanism for typewriting machines, the combination of a member having a single normal position, a ribbon carrier connectible with said member at any one of a plurality of connecting points, actuating devices for said member, and means for varying the effect of said actuating devices on said member. 90

4. In a typewriting machine, the combination of a ribbon carrier, an operating lever, means for affording variation in the normal relationship between said carrier and said lever, actuating devices for said lever, and means for varying the normal relationship between said actuating devices and said lever. 95 100

5. In a typewriting machine, the combination of a ribbon carrier, an operating lever therefor, means independent of the operation of the machine for affording a change in the normal relationship between said carrier and said lever, and means for variably actuating said lever at printing operation. 105

6. In a typewriting machine, the combination of a ribbon operating lever having a single normal position, a ribbon carrier connectible therewith at any one of a plurality of connecting points, a key operated universal bar, connections between said universal bar and said lever comprising a link, and means for varying the normal relationship between said link and said lever. 110 115

7. In a typewriting machine, the combination of a ribbon operating lever having a single normal position, a ribbon carrier connectible therewith at any one of a plurality of connecting points, a key operated universal bar, connecting devices between the same and said lever, and means for varying the normal relationship of said connecting devices, said last recited means comprising a hand operated controlling member having a plurality of faces adapted to co-act with said link. 120 125 130

8. In a typewriting machine, the combination of a ribbon carrier, a guide therefor having a single normal position, means for vibrating said carrier independently of said guide, and means for affording movement of said guide to permit the normal position of said ribbon carrier to be varied.
9. In a typewriting machine, the combination of a ribbon carrier, a pivoted guide having a single normal position, and means for vibrating said carrier on said guide and independently thereof at printing operation; said carrier being movable with said guide when said guide is turned on its pivot independently of the printing operation of the machine.
10. In a typewriting machine, the combination of a ribbon carrier, a guide therefor comprising two parts, one guide part being pivoted on the other, a spring maintaining said guide parts in normal relationship, means for actuating said carrier independently of said guide, said carrier being movable with one of said guide parts when the same is turned on its pivot against the pressure of said spring.
11. In a typewriting machine, the combination with a ribbon carrier, a carrier guide, and devices for actuating said carrier at printing operation, said guide being movable to permit a change in the point of connection between said ribbon carrier and certain of said devices.
12. In a typewriting machine, the combination of a ribbon carrier, a carrier guide having a single normal position and on which said carrier is slidable, and actuating devices for said carrier, said guide being movable to afford a change in the normal relationship between said carrier and said actuating devices.
13. In a front strike typewriting machine, the combination of a ribbon carrier, an upright carrier guide on which said carrier is vertically slidable at printing operation, and actuating devices for said carrier including a lever, said guide being movable to disconnect said carrier from said lever and affording independent movement of said carrier so that the same may be connected at a different point with said lever.
14. In a front strike typewriting machine, a pivoted spring pressed carrier guide, a ribbon carrier vertically slidable on said guide, actuating devices including a horizontal operating lever pivotally connected with said carrier, said carrier being pivotally movable to permit disconnection of said carrier from said lever and re-connection of said carrier with said lever at a different point.
15. In a typewriting machine, the combination of a pivoted carrier guide, a ribbon carrier slidable thereon and provided with a plurality of cross pins, and actuating devices including a lever having a slotted end adapted to engage with said cross pins, said guide being pivotally movable to afford connection of any desired cross pin with said lever.
16. In a typewriting machine, the combination of a ribbon carrier, devices for throwing the carrier different extents to present different widthwise portions of the ribbon to the printing point, and means for affording a change in the relationship between said carrier and said devices whereby the ribbon when thrown one extent will be presented to the types and when thrown a different extent will fall short of the printing point.
17. In two-color ribbon mechanism for writing machines, the combination of a ribbon carrier, devices for throwing the same to present one ribbon field to the printing point, said devices being adjustable so that when thereafter actuated a different ribbon field will be presented to the printing point, and means independent of said devices for setting said ribbon carrier so that said devices when actuated will present one ribbon field to the types and when re-adjusted will when actuated fail to present either ribbon field to the types.

Signed at Syracuse, in the county of Onondaga, and State of New York, this 7th day of July, A. D. 1910.

HERBERT H. STEELE.
